UNITED STATES PATENT OFFICE.

EDWARD H. WEGNER, OF CAMERON, IDAHO.

CARPET-STRETCHER.

953,877.

Specification of Letters Patent. Patented Apr. 5, 1910.

Application filed September 27, 1909. Serial No. 519,697.

To all whom it may concern:

Be it known that I, EDWARD H. WEGNER, a citizen of the United States, residing at Cameron, in the county of Nez Perce, State 5 of Idaho, have invented certain new and useful Improvements in Carpet-Stretchers; and I do hereby declare the following to be a full, clear, and exact description of the invention, such as will enable others skilled in 10 the art to which it appertains to make and use the same.

This invention relates to improvements in carpet stretchers.

The object of the invention is to improve 15 the construction of carpet stretchers and to provide a simple and inexpensive device of this character which is adapted to simultaneously stretch the four sides of a carpet and which may be readily and easily adjusted 20 so as to be applicable to various sizes of carpets.

To this end the invention consists in the details of construction and combination of parts to be hereinafter more fully set forth 25 and particularly claimed.

In describing the invention in detail reference will be had to the accompanying drawings wherein like characters of reference denote corresponding parts in the several views, and in which,

Figure 1 is a top plan view of the invention in the position it occupies previous to applying pressure thereto to stretch a carpet; Fig. 2, a section on the line 2—2 of 35 Fig. 1; Fig. 3, a section on the line 3—3 of Fig. 1; the stretcher being completely expanded; Fig. 4, a section on the line 4—4 of Fig. 1; and, Fig. 5, a detail perspective view of one of the stretcher bars.

Referring to the drawings, A indicates the central frame of the structure formed of four side members. One pair of opposite side members 6 being each formed of a single piece of material, while the other pair 45 is each constructed of two separate sections 7 and 8. The said sections 7 being reduced in width throughout the greater portion of their length to form the tongue 9, while the sections 8 are each provided with a slot 10 adapted to receive the tongue 9 so as to permit a free movement of the tongue in said slot when desired. A series of apertures 11 50 extend transversely through the tongue 9

and a corresponding series of apertures 12 extend through the arms of the section 8 so 55 that during the movement of the tongue 9 into the slot 10 the outermost aperture 11 will successively pass into registration with all of the apertures 12. By this construction it will be apparent that the side members of the frame constituted by sections 7 and 8 can be lengthened and shortened and maintained a desired length by the insertion of the bolt 13 in the registering apertures 11 and 12. 60

Extending laterally from the frame A on opposite sides thereof and secured to the sections 8 through the medium of the hinged connection 14 are stretcher bars each constructed of two separate sections 15 and 16. 70 The sections 16 are reduced in width throughout the greater portion of their length to form the tongue portion 17 while the sections 15 are provided with a slot 18 adapted to receive the tongue 17 and permit a free 75 longitudinal movement of the tongue therein. A series of apertures 19 extend transversely through the tongue 17 and a corresponding series of apertures 20 extend through the arms of the sections 15 so that 80 during the movement of the tongue 17 into the slot 18 the outermost aperture 19 will successively pass into registration with all of the apertures 20. It will thus be evident that the stretcher bars constituted by 85 the sections 15 and 16 can be lengthened and shortened and further, they may be maintained the desired length by the insertion of the bolts or pins 21 in the registering apertures 19 and 20. 90

Secured to each of the sections 8 of the frame A through the medium of a suitable hinged connection are the stretcher bars 22 which are also constructed in two sections and are adapted to lengthen and shorten. 95 Said stretcher bars 22 are located in respective parallel spacement to the stretcher bars which are formed of the sections 15 and 16 and as they are identical in construction to the latter a detail description thereof will be 100 omitted. A toothed bar 23 having its under face provided with a series of carpet engaging teeth 24 is hinged to the outer end of each stretcher bar 22 and the stretcher bar which is constructed of the sections 15 and 105 16 and which are disposed on the same side

of the frame A. The bar 23 has hinged at each end lengthening sections 24 adapted to be brought into use as the frame is expanded. Each of the side sections 6 of the frame 5 A has hinged thereto in a suitable manner a pair of stretcher bars 25 arranged in parallel spacement to each other. Each pair of stretcher bars 25 has hinged to their outer end a toothed bar 26 similar in construction 10 in every respect to the bar 23 previously described. Each of the bars 26 is provided with lengthening sections 27 hinged thereto at its terminals.

In order to more effectually stretch the 15 carpet in the direction of the corners of a carpet, a series of similarly constructed stretcher bars are secured to the frame A through the medium of the hinged connection 28. These stretcher bars are located at 20 each corner of the frame A and are constructed of two sections 29 and 30, the former of which is provided on its under face with carpet engaging teeth 31 and is reduced in width throughout the greater portion of 25 its length to form the tongue 32 while the section 30 is provided with a slot 33 to receive the tongue 32 and permit a free movement of the tongue therein when desired. A series of apertures 34 extend transversely 30 through the tongue 32 and a corresponding series of apertures 35 extend through the arm of the section 30 so that during the movement of the tongue 32 into the slot 33 the outermost aperture 34 will successively 35 pass into registration with all of the apertures 35. By the construction just described it will be obvious that the stretcher bars formed of the sections 29 and 30 can be lengthened and shortened at will and maintained a desired length by the insertion of 40 the bolt 36 in the registering apertures 34 and 35.

The operation of the device will be obvious; it being only necessary to adjust the 45 various stretcher bars to the desired length and apply the stretcher to the carpet in the position shown in Fig. 2, when a downward pressure exerted upon the center frame A will cause said stretcher to assume the position shown in Fig. 3 and thus effectually stretch the carpet in the desired position for inserting the necessary tacks. It will also be 50 equally obvious that the stretcher is adjustable in two directions at right angles to each other, in one direction through the medium of the adjustable stretcher bars 22 and those formed of the sections 15 and 16, and in the 55 other direction through the medium of the adjustable sides of the central frame A.

60 What is claimed is:—

1. A carpet stretcher comprising a central frame, a series of stretcher bars hinged to said frame, means for lengthening and shortening said frame in one direction and 65 means for lengthening and shortening cer-

tain of said stretcher bars in a different direction.

2. A carpet stretcher comprising a central frame, having a pair of oppositely disposed sides constructed of telescoping sections 70 whereby said frame may be lengthened and shortened in one direction, and a series of stretcher bars hinged to said frame, certain of said stretcher bars being also constructed of telescoping sections, whereby they may be 75 lengthened and shortened in a different direction.

3. A carpet stretcher comprising a central frame, having a pair of opposite sides each constructed of sections, one of which sections is formed with a tongue provided transversely with apertures and the other with a slot for receiving said tongue and having apertures passing through the arms formed by said slot and adapted for variable 80 registration with the apertures of the tongue, locking means adapted to pass through the registering apertures of said sections, whereby they may be locked in a desired relation, a series of adjustable stretcher bars hinged 85 to the adjustable sides of said frame and a series of non-adjustable stretcher bars hinged to the non-adjustable side of said frame.

4. A carpet stretcher comprising a central 95 frame, having a pair of opposite sides adjustable whereby said frame may be lengthened and shortened in one direction, a series of stretcher bars hinged to the adjustable side of the frame, each of said bars being 100 constructed of sections, one of which is formed with a tongue provided with transverse apertures and the other with a slot for receiving said tongue and having apertures passing through the arms formed by said slot and adapted for variable 105 registration with the apertures of the tongue, locking means adapted to pass through the registering apertures of said sections, whereby they 110 may be locked in a desired relation and adjustment, and a series of non-adjustable stretcher bars hinged to the non-adjustable side of the frame.

5. A carpet stretcher comprising a central frame, a series of stretcher bars hinged to 115 said frame at right angles to the respective sides thereof, means for lengthening and shortening said frame in one direction, means for lengthening and shortening certain of said stretcher bars in a different direction and an adjustable stretcher bar hinged to each corner of said frame adapted to be disposed in alinement with the diagonal of the frame passing through the corner to which said stretcher bar is hinged.

6. A carpet stretcher comprising a central frame, a series of stretcher bars hinged to each side of said frame, and a toothed bar hinged to the outer ends of the stretcher bars disposed on the same side of the frame.

7. A carpet stretcher comprising a central frame, a series of stretcher bars hinged to each side of said frame, means for lengthening and shortening said frame in one direction, means for lengthening and shortening certain of said stretcher bars in a different direction, a toothed bar hinged to the outer end of the stretcher bars disposed on the

same side of the frame and means for lengthening and shortening said toothed bar. 10

In testimony whereof, I affix my signature, in presence of two witnesses.

EDWARD H. WEGNER.
